UNITED STATES PATENT OFFICE.

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA.

HIGH-POTENTIAL ARCING DEVICE.

Application filed September 23, 1922. Serial No. 590,153.

My invention relates to arcing devices and particularly to arcing devices for high-potential insulators.

One object of my invention is to provide a device of the above-indicated character that shall present a relatively great surface area to the electrostatic forces of a high-potential insulator and that shall be extremely light in weight.

Another object of my invention is to provide an arcing device for high-potential insulators that shall greatly facilitate its installation and that shall be effective in its operation.

Another object of my invention is to provide an arcing-ring device that shall be effective in connection with circuits of higher voltages than devices of similar character heretofore used or, in other words, an arcing-ring device by the use of which the said circuits of higher voltages may be more effectively employed.

A further object of my invention is to provide a high-potential arcing device that shall be simple and durable in construction and economical to manufacture.

In the development of high-potential transmission lines, each appreciable advance in the value of the voltage at which it is desired to operate incurs new problems of construction and design. One of the principal difficulties attaching to the increase in voltage of transmission lines is to overcome the corona effect. Also, the direction and distribution of the electrostatic field are factors of great importance in the attainment of a highly effective insulator. Arcing ring members, similar to my invention, have heretofore been suggested but, to the best of my knowledge, none of them has been similarly adapted for the increased voltages of later developments in the art.

Arcing-ring members, as initially suggested, were employed merely as means for directing the flash-over arc, as is attested by the small cross-sections of the rings. Also, the arms for the support of the rings had, in certain structures, sharp edges and ends overlapping the perimeters of the rings in such manner as to increase the corona effect, and to cause flash-over or breakdown at voltages below that which they might otherwise withstand.

In practicing my invention, I provide an arcing-ring structure, preferably constructed

of relatively light sheet metal and tubular members, in which all sharp edges and corners are so shielded by relatively broad expanses or areas of conducting material as to widely distribute the electrostatic stresses, to reduce the corona effect and, at the same time, to so direct the flash-over arc as to protect the insulator from damage.

Figure 1 of the accompanying drawing is a broken plan view of an arcing-ring device constructed in accordance with my invention, and

Fig. 2 is a side view, partially in elevation and partially in section, of the device shown in Fig. 1, with the insulator and other parts indicated in broken lines.

The device comprises, in general, a main arcing or field-distributing ring member 2, a relatively small supporting ring member 3 therefor, arms 4 for connecting the rings 2 and 3, a supporting member 5 connected between the ring 3 and an insulator 6, and a clamp 7 for supporting a high-potential conductor 8. The insulator 6 is preferably of a usual suspension type, the particular construction of which is not germane to this invention, except in so far as the relative sizes and general relation of parts are concerned.

The main ring member 2 is preferably constructed, of relatively thin sheet metal, to be of inverted substantially U-shape in cross section, as shown, in which the trough 9 of the U is of relatively great radius and the outer leg 10 of the U is longer than the inner leg 11. This construction provides a relatively great conducting surface area,

The supporting member 5 has an end portion 12 for attachment to the insulator 6, by a bolt 14, and depending arm portions 15 having laterally projecting portions 16 for attachment to the smaller ring 3, by bolts 17. The ring 3 is preferably of substantially flat-washer shape having its inner edges sufficiently spaced from the longitudinal axis of the insulator to admit the clamp 7. The latter is secured to the arm portions 15 of the member 5 by a bolt 18.

The arms 4, preferably of arcuate shape substantially throughout the length thereof and constructed of relatively thin sheet-metal tubing, are provided with flattened ends 19 and 20 for attachment to the rings 2 and 3, respectively. The ends 19 are attached, by bolts 21, to lugs 22 secured to the inner sur-

face of the ring 2, and the ends 20 are attached, by bolts 23, to the ring 3. The relatively great surface area of the ring 2 serves to widely distribute the electrostatic field and to thus reduce the tendency to form corona. The ends 19 of the arms 4, being inside the ring 2, do not attract or serve to concentrate the electrostatic field at these points. The arms 4, being well-rounded and arcuate substantially throughout the lengths thereof, present no sharp bends, edges or corners to the field. The general construction throws all of the main broad rounded surfaces up and away from the clamp 7, and the parts adjacent thereto, so that the tendency to form corona is very materially reduced.

The relatively thin sheet metal employed permits the increased surface areas to be attained without undue increase in the weight of the structure. Further, an arcing device is provided that is simple and durable in construction, economical in manufacture and effective in its operation.

While I have shown and described a particular form of my invention, changes may be effected therein without departing from the spirit and scope thereof, as set forth in the appended claims.

I claim as my invention:

1. The combination with a high-potential insulator, of an arcing device therefor comprising a relatively large sheet-metal arcing ring of inverted substantially U-shape in cross-section and having the outer leg of the U longer than the inner leg thereof, a metal member pivotally connected at its upper end to the insulator and having a plurality of depending arms, said arms having laterally-projecting portions, a relatively small supporting ring of substantially flat-washer shape attached to said laterally-projecting portions, and a plurality of arcuate tubular members having flattened ends connected to said longer leg of the arcing ring and to said supporting ring.

2. An arcing device comprising a ring of sheet metal of substantially U-shape in cross section, in which the legs of the U are at least as far apart as the diameter of the closed end thereof and extend in the general direction of the axis of the ring.

3. An arcing device comprising a ring of sheet metal of substantially U-shape in cross

section, in which the legs of the U lie substantially parallel to the axis of the ring and are at least as far apart as the diameter of the closed end of the U, and a structure adjacent to the center of the ring embodying a portion for mounting the device and a portion extending substantially radially from said mounting portion to said ring and connected to the latter at a position between said legs.

4. An arcing device comprising a ring of sheet metal of substantially U-shape in cross section, in which the legs of the U are at least as far apart as the diameter of the closed end thereof, and a central structure embodying longitudinally offset portions for mounting the device and supporting the ring, respectively, said supporting portion providing a space for the reception of a portion of a conductor clamp, and a portion extending substantially radially from said supporting portion opposite an intermediate portion of said clamp to said ring at a position between said legs.

5. An arcing device comprising an arc-receiving ring for disposition around the axis of an insulator, and a central structure embodying a central portion for mounting the device, laterally-spaced, longitudinally-extending portions closely associated with said central mounting portion for receiving a portion of a clamp therebetween, and portions extending substantially radially from said longitudinally-extending portion opposite an intermediate portion of said clamp to said ring for supporting the latter.

6. The combination with a high-potential insulator, of an arcing device therefor comprising a sheet-metal arcing ring of inverted substantially U-shape in cross section and having one leg of the U longer than the other, a metal member connected at its upper end to the insulator and including a depending portion having a laterally-projecting portion, a relatively small supporting ring attached to said laterally-projecting portion, and a plurality of members connected between said longer leg and said supporting ring.

In testimony whereof, I have hereunto subscribed my name this 30th day of August, 1922.

NILS A. WAHLBERG.
